J. C. SLAUGHTER, OF CRUMPTON, MARYLAND.

Letters Patent No. 77,926, dated May 12, 1868.

IMPROVEMENT IN CHURNS.

The Schedule referred to in these Letters Patent and making part of the same.

TO ALL WHOM IT MAY CONCERN:

Be it known that I, J. C. SLAUGHTER, of Crumpton, Queen Anne county, Maryland, have invented an Improvement in Churns; and I do hereby declare the following to be a full, clear, and exact description of the same.

My invention consists of a casing, contracted in diameter at the lower end, and containing revolving blades or beaters, arranged as fully described hereafter, so that while the apparatus is adapted for holding and churning a large quantity of cream, it will operate as effectually when the quantity of cream is greatly reduced.

In order to enable others skilled in the art to make and use my invention, I will now proceed to describe its construction and operation, reference being had to the accompanying drawing, which forms a part of this specification, and in which—

Figure 1 is a sectional elevation of my improved churn.

Figure 2, a section on the line 1-2, fig. 1; and

Figure 3, a plan view, partly in section.

A is a casing, which is cylindrical from the upper edge to the line z z , but contracts gradually in diameter below this line; and on a ledge, b, near the upper edge of the casing, rests a cap or cover, B, consisting of three sections, a a^1 a^2 , the sections a a^1 being hinged together, and pins c c , at the inner edge of the section a^2 , extending into recesses in the section a^1 , fig. 3.

In a "step," at the bottom of the casing, rests the lower end of a shaft, C, which extends through the cap B, and has at its upper end a bevel-pinion, e; the teeth of the latter being adapted to those of a bevel-wheel, f, on a shaft, D, turning in a bracket, E, secured to the section a^1 of the cover.

To the shaft C is hung a frame, G, the shaft passing through a sleeve, h, at the upper end of the frame, and near its lower end, through a yoke, i, the frame corresponding in form with the casing A, as shown in the drawing.

Across the frame extend blades, m, which are closer together at the lower than at the upper end, for a purpose described hereafter; and from the shaft C project blades n, which are arranged midway between the blades m of the frame.

The sleeve h projects through the cap B, and has, at its upper end, a bevel-pinion, e', the teeth of which are adapted to those of the toothed wheel f. At the outer end of the shaft D is a crank-handle, F, and from the section a^2 , project pins o, fig. 3, which are adapted to L-shaped slots s, near the upper edge of the casing; a pin, o', projecting from the section a into a notch or recess, s', in the casing.

After the cream is placed in the churn, the parts are arranged as shown in the drawing, and the shaft D is turned, when the shaft C and the frame G will be caused to revolve rapidly in opposite directions, thereby so thoroughly agitating the cream that butter is quickly obtained.

The ordinary churning are generally of the same diameter, or nearly of the same diameter, at the lower as at the upper ends, so that although efficient in their operation when nearly filled with cream, they will not act upon small quantities of cream, which, in receptacles of such considerable diameter, cannot cover more than one or two of the blades; the latter therefore failing to produce such an agitation of the cream as is necessary to extract the butter.

By the use of a casing contracted in diameter near its lower end, in connection with revolving blades, arranged nearer together at the lower than at the upper part of the casing, the smallest quantity of cream which it is desirable to churn will cover such a number of blades or beaters that the latter cannot fail to thoroughly agitate it, while the capacity of the churn is not materially reduced, and its efficiency in operating upon larger quantities of cream is not impaired.

In securing the lid or cover, the section or plate a^2 is first introduced into the casing, so that the pins o will pass into the vertical portions of the L-shaped openings s, and, after the plate is in contact with the ledge b, it is turned so as to carry the pins into the horizontal portions of the slots, the plate being thus prevented from rising. The shaft and frame are now adjusted, and the sections a a^1 are placed upon the ledge b, the pin o'

projecting into the recess s' , and thus preventing the turning of the cap as long as the section a is in its place, so that the cap is firmly secured in its position without the use of detachable fastening-devices, which are liable to be lost, to get out of order, and are difficult to manipulate.

When access is desired to the interior of the churn, only the portion a is raised. If desired, however, a single section or plate may be substituted for the two sections a a' .

Inasmuch as the shaft C is at one side of the blades of the frame G , these blades may extend entirely across the frame, instead of being divided at the centre, for the passage of the shaft, as in ordinary churns having beaters of this class. The cost of constructing the beaters is thus reduced, while they are much more durable than those made in the usual manner.

I do not claim a revolving shaft and blades in combination with a revolving frame; but I claim as my invention, and desire to secure by Letters Patent—

1. A casing, A , contracted in diameter near the bottom, in combination with a series of revolving blades, m , arranged nearer together at the lower than at the upper end of the casing, for the purpose set forth.

2. The frame G , having blades n extending across the same, and hung to the shaft C , in respect to its blades m , as and for the purpose specified.

In testimony whereof, I have signed my name to this specification in the presence of two subscribing witnesses.

J. C. SLAUGHTER.
